Inventor
Morris Friedman
By his Attorney
Charles G. Hensley.

UNITED STATES PATENT OFFICE.

MORRIS FRIEDMAN, OF BROOKLYN, NEW YORK.

DEVICE FOR AIDING THE HEARING.

Specification of Letters Patent. Patented Oct. 15, 1918.

1,281,550.

Application filed March 31, 1916. Serial No. 87,900.

To all whom it may concern:

Be it known that I, MORRIS FRIEDMAN, formerly a subject of the Emperor of Austria, having declared my intention of becoming a citizen of the United States, and residing in the borough of Brooklyn, city of New York, county of Kings, and State of New York, have invented certain new and useful Improvements in Devices for Aiding the Hearing, of which the following is a specification.

My invention relates to a device for aiding the hearing and it belongs to the class of microphonic electric devices used by persons who are hard of hearing or partially deaf in order to aid them in hearing. The present invention relates more particularly to the instrument wherein the sound waves are translated into electrical pulsations, or to the instrument commonly called the transmitter.

The object of my invention is to provide a device of this character which will be more sensitive to sounds and which will cause electrical pulsations in the circuit capable of louder reproduction in the reproducer, so that the device will be more efficient than those heretofore made. Another object of my invention is to provide a device which will render the reproductions of sounds clearer and more natural or more nearly like the actual sounds which act upon the transmitter. These results are accomplished by arranging the sound passages in the transmitter in a novel manner.

In the drawings forming part of this application,

Figure 1 is a sectional view through the middle of a transmitting instrument made in accordance with my invention, and in which view, the circuit is shown diagrammatically.

Fig. 2 is an enlarged sectional view of a portion of the diaphragm and its casing.

Fig. 3 is a sectional view, taken on the line 3—3 of Fig. 1,

Fig. 4 is a sectional view on the line 4—4 of Fig. 1, and

Fig. 5 is a face view of the device, looking at the front.

Fig. 6 is a detail view.

The device consists principally of a microphonic part including a diaphragm, and sound receiving and conducting parts. The outer member or container consists of a casing or shell 1 which comprises a rear

wall 2 having an opening to receive therein the rheostat 3, which seats on the rabbet 4, of a flange 5 around the outer edge of the wall 2; and of a second member 6 comprising a front wall 7 and a flange 8 around its edge. The flange 8 slides over or telescopes in relation to the flange 5 when the parts are assembled, so that the members 1 and 6 form an inclosure or sound chamber. The front wall 7 has one or more apertures 9 disposed at or near its central portion, and these apertures are here shown as countersunk, with the larger portion to the outside. The casing members inclose the microphonic device.

There is an interior shell or box 10 which consists of front and rear sections, which have flanges 11, 12 and which latter are threaded, so that one screws into the other so that the two shell members when united form an interior chamber. The front member has a front wall 13, to which the carbon cup 14 is fastened by means of a screw 15 passing through the wall. This wall 13 is otherwise imperforate, or at least it is made so that sound waves may reflect upon it but no apertures are provided for the sound to pass directly therethrough.

A diaphragm 16, preferably of the same material that diaphragms of this character are made of, is clamped against the member 17 by the flange 12 acting on its edge, and I have shown a paper washer 18 lying against the diaphragm edge for purposes well known.

The pockets 19 in the carbon cup are partly filled with small, loose carbon balls 20 which form in well known manner, a microphonic connection between the cup 14 and the diaphragm.

The rear wall 21 of the inner casing or shell 17, has perforations 22 in the form of an annular ring near the outer edge of the wall and these are preferably drilled on angles oblique to the plane of the wall, as shown in the drawing.

The rheostat 3 consists of an insulating support or disk which sets in the aperture in the wall 2 and flush with the outer surface of the wall; of coils of wire (not shown) offering different resistances to the flow of current in the circuit, according to how many such coils are connected in the circuit; and of contact points 23 connected with the several coils and with which points the switch lever 24 cooperates. There is a

bushing 25 which is screwed into the wall 21, and a screw 26 threaded into one end of this bushing forms the support for the switch lever 24.

5 The inner shell is preferably held in place by screws 27 which pass through the depressed or rabbet portion of the wall 2 and the wall 21 of the inner shell, and these screws alternate in position with the screws

10 28 which hold the rheostat around the circle. Binding posts 29, 30 on the casing member 6 are adapted to be connected in series in a circuit which includes a source of current, such as the battery 31 and a receiver

15 32. The latter may comprise any well known receiver adapted for the purpose, its function being to transform the electrical impulses into sound waves. From one binding post a wire 33 connects with a plate 34 lying in contact with the carbon cup and which plate is insulated from the inner shell or casing by the insulating plate 35.

A wire 36 extends from the other binding post to one end of the rheostat, which latter has its other end grounded on the outer casing and therefore in electrical connection with the diaphragm. The circuit is the usual one employed in devices of the kind, so that further description thereof is not

30 necessary here. The device herein shown is generally hung or worn on the person using it so that the diaphragm is in substantially a vertical plane in order that the microphone will be most sensitive to sound. If worn against the body, the wall 7 will be turned away from the body in order that the sound waves may freely enter the apertures 9 in the central portion of the wall.

40 As the sound waves enter the apertures 9 they spread out laterally and pass through the space 37 formed between the walls 13 and 7. They then pass through the space 38 formed between the edge of the inner shell and the outer casing, and enter the space 39 between the rear wall 2 and the rear wall 21 of the inner shell. From there the waves pass through the annular ring of apertures 22 and then act upon the dia-

45 phragm. It is understood, of course, that the movements of the diaphragm are translated by the microphonic connection into electrical pulsations which pass through the

circuit and are translated into sound waves in the receiver.

I find that the improved results are accomplished to a great extent by taking the sound waves in at a central part, such as the central portion of the wall 7 and by expanding them laterally, as in the space 37. 55 and by causing them to afterward impinge or act upon the diaphragm. In my experiments I found that the results accomplished were much less when the casing member 6 was removed and the device used without it than when used with this member. I also found that the results were much inferior with a member 6 having perforations only in an annular ring near the outer edge of the wall 7, the other parts of the device remaining the same. I therefore attribute the improved results to a great extent to the receiving of the waves through the centrally arranged apertures 9 and to their lateral expansion in the space 37. The best 70 results are obtained when the distance between the inner shell and outer shell is the same at the spaces 37, 38 and 39. The result is improved also by arranging the device so that the sound waves first approach 75 the outer portion of the diaphragm. The space 40 between the diaphragm and the wall 21 is very thin or shallow, so that the sound waves have a strong effect upon the diaphragm.

80 It is obvious that the device is not necessarily limited in its use to the purpose herein indicated as it may be used wherever a microphonic transmitter is required.

Having described my invention, what I 85 claim is:

A microphone comprising an outer casing having a sound receiving opening centrally disposed in one wall thereof, an inner shell spaced from said outer casing to form 90 a sound space expanding laterally from said sound receiving opening and passing around said inner shell, a diaphragm in said inner shell, said inner shell having annularly disposed openings in its rear wall for admitting sound waves to the outer portion of the diaphragm.

100 Signed at the city, county and State of New York, this 24th day of March, 1916.

MORRIS FRIEDMAN.
